TITLE SPACER

Robert J. Rodtz, Sr., 145 Dubois Ave., West New
Brighton, Staten Island 10, N.Y.
Filed Sept. 24, 1958, Ser. No. 763,041
4 Claims. (Cl. 33—180)

This invention has reference to a set of spacer members which is especially well adapted for use for aligning and spacing tiles on floors, walls and like supporting surfaces. The present invention is related to Patent 2,930,135, issued to me March 29, 1960.

In aligning and spacing of tiles on a supporting surface by the method practiced heretofore, as it is well known, the mechanic makes use of two reference lines, generally in the form of cords disposed at right angles to each other and tensioned in parallel relation to two adjacently disposed side walls of a room for example, to serve as guides for aligning the first two coordinately disposed rows of tiles to be cemented onto the floor or walls of such room, these rows of tiles in turn serving as guides for the aligning of successive rows of tiles in both directions, that is at right angles to each other.

While that practice has been found to somewhat assist in laying the first two coordinately disposed rows of tiles in an approximately straight line, the final alignment and the spaced relation between the tiles in these first two rows and the consecutive rows is effected by sight approximation, resulting in considerable difference in the spaced relation between adjacently disposed tiles and between each row of tiles in the two directions, this difficulty in laying tiles by the use of the method practiced heretofore, as above mentioned, being rendered still more difficult because of the fact that considerable variation exists in the dimension and angularity of the tiles with the result that a side of a tile aligned with the cord and with the sides of the other tiles in a row, the opposite side of such tile obviously did not fall in alignment and in spaced relation with other tiles in other rows, thus necessitating the removal of all the tiles and the repeating of the aligning and cementing operation, such method of laying tiles as to straight line alignment of the rows, as to parallelism of the rows, space relation between the tiles and angular relation of the tiles relative to each other forming the rows, has been found to be a time consuming operation, difficult and unpracticable even to highly skilled mechanics.

The object of the present invention resides in the provision of a set, or combination, of spacer members whereby the angular and spaced relation and the alignment of the tiles may be effected in a simple and accurate manner by any inexperienced person, while requiring only a minimum of time and expenses.

The novel features of the invention and advantages will appear from the following description and by the claims appended thereto, reference being had to the accompanying drawing in which:

FIG. 1 is a view in perspective of a four integrally formed arm spacer member constructed according to the present invention, the arms being bowed in the form of semi-crescents and disposed at right angles to each other in the form of a cross-shaped figure;

FIG. 2 is a view in perspective of a three integrally formed arm spacer member which is a derivative of the spacer member shown in FIG. 1 substantially forming a capital letter T adapted to be used in conjunction or in combination with the cross-shaped spacer member shown in FIG. 1;

FIG. 3 is a view in perspective of a two integrally formed arm crescent-shaped spacer member which is another derivative of the spacer member shown in FIG. 1

2

for use in combination with the spacer members shown in FIG. 1 and 2, in a tile aligning and spacing operation;

FIGS. 1A, 2A and 3A are side views of the spacer members turned clockwise 45° from the position indicated in FIGS. 1, 2 and 3, respectively, to show the thickness variation of the spacer arms from end to end, one of such arms, FIG. 1A, being shown with a portion broken away;

FIG. 4 is a side view of the spacer members shown in FIGS. 1, 2 and 3 slightly modified, one arm of one such spacer members being shown in section taken on line 4—4 of FIG. 5, the supporting surface being shown in section and with portions broken away; and

FIG. 5 is a plan view showing one set of spacer members in position relative to a plurality of tiles and relative to two straight edges used for moving the tiles and the spacer members in spaced and aligned relation to each other on the supporting surface for the tiles.

According to the present invention, the set of spacer members S¹, S² and S³, shown in FIGS. 1, 2 and 3 respectively, may be constructed of any desired hard material. The spacer member S¹, as shown in FIG. 1, consists of four integrally formed arms 10, 11, 12 and 13, disposed at right angles to each other, forming a geometrical figure representing a cross with the arms bowed or curved in the form of a crescent, the height of which from its narrow edge portions corresponds to substantially twice the thickness of the tiles and with the transverse dimension of these arms made to correspond to the width 20 of the joint desired between the tiles, while the thicknesses of the arms 10—11 and 12—13, which are disposed in straight line alignment form as above mentioned two crescent-shaped figures the ends of which serve as bearing points on which the spacer is adapted to rest, 25 while that portion or junction point of the arms which extend above the plane surface of the tiles where the crescent has the greatest thickness, serves to prevent the accidental deformation of the arms in the handling of the spacers while in actual use. Spacer S¹ is adapted to 30 be placed as for example in position at the adjacently disposed corners of four tiles as T1, T2, T3 and T4, or at the adjacent corners of tiles T2, T4, T5 and T6, to be aligned either by the use of the combination of the spacer, shown in FIGS. 1, 2 and 3, or the combination 35 of the spacer comprising the spacer members S¹, S² and S³, shown in their respective position between the tiles in FIG. 4.

The spacer member S², as shown in FIG. 2, is formed with three arms 14, 15 and 16, of variable thickness from end to end, the arm 16 extending at right angles to the rectilinear or straight aligned arms 14—15 to form therewith substantially a capital letter T, while the arm 16 is joined to the arm 14—15 at the middle length of the crescent-shaped figure thus formed. In actual use 50 the arm 16 of spacer member S², as best seen in FIG. 5, is adapted to be placed between the adjacently disposed corners T3y and T4y of the tiles T3 and T4 for example, or the opposite corner of tile T4 and the corner T6y of tile T6, while the arms 14—15 of spacer members S² occupy a space between the corners of the tiles and a straight edge ST1 used for imparting a side way movement to the tiles and to the spacer members collectively 55 for aligning them relative to each other and relative to the baseboard wall of a room, not shown, as will be hereinafter described in detail.

The spacer member S³, shown in FIGS. 3 and 5, is constructed with two arms 17 and 18 disposed in straight line alignment and bowed to form a crescent-shaped figure. The transverse width of the arms of spacer member S³, like the end portions of arms 10—11 and 12—13 of spacer member S¹ and the arms 14, 15 and 16 of spacer member S², corresponds to that of the width of the

3

joints desired between the tiles as T5 and T6, or the joints between the tile T6 and the straight edge ST1, as shown in FIG. 5.

The free ends of the rectilinear or straight line disposed arms 10—11 and 12—13 which form the cross-shaped figure S1 shown in FIG. 1, the free end of each arm 14—15 and 16 forming spacer member S2 shown in FIG. 2, and the free end of each rectilinear disposed arms 17 and 18 forming spacer member S3 shown in FIG. 3, terminate with a small contact area, or narrow edge, to serve as above mentioned bearing surfaces adapted to rest over the adhesive covered supporting surface for the tiles for supporting their respective spacer members in the position best indicated in FIGS. 4 and 5, while the small contact area of the bearing surface at the ends of the arms has been found to greatly facilitate the removal of the spacer members from between the aligned tiles, substantially free of adhesive, and therefore without the liability of disturbing the aligned relation of the tiles upon the removal of the spacers from the supporting surface.

The spacer members S1y, S2y and S3y, shown in FIG. 4, are modifications of the spacer members S1, S2 and S3 above described, in that the spacer members S1y, S2y and S3y are adapted to be punched from a metallic sheet with the arms 17y and 18y of spacer member S3y curved to form substantially a semicircle, the arms 14y, 15y and 16y of spacer member S2y forming a capital letter T and the arms 10y, 11y and 12y of spacer member S1y forming a cross with the arms bowed to a radius of a length substantially twice the thickness of the tiles with which these spacers are used. These spacer members thus formed are afterwards submitted to a hardness treatment for increasing the rigidity of the material, while the transverse width of the arms 10y-11y and 12y-13y of spacer member S1y, like the spacer member S1 shown in FIG. 1, corresponds to the space desired between the adjacent corners of tiles T1, T2, T3 and T4, or the tiles T2, T4, T5 and T6, while the junction portions of the arms which protrude above the top surface of the tiles form means in the form of a handle adapted to be gripped by the fingers for placing in or removing the spacers from between the tiles following their alignment onto the adhesive covered supporting surface.

The spacer member S2y, FIG. 4, which, as above mentioned, is a modification of the spacer member shown in FIG. 2, consists of three arms 14y, 15y and 16y extending at right angles to each other, this spacer member, like the spacer members S1y and S3y, may be punched from a sheet metal with the arms 14y, 15y disposed in straight line alignment and bent to form a semicircle having a radius like the arms of spacer member S2, which is substantially twice the thickness of the tiles, while the arm 16y forms a quarter of a circle thus completing a capital T shaped figure adapted for use in a manner similar to that of spacer member S2 shown in FIGS. 2 and 5.

The spacer member shown in figure S3y may be punched from a sheet metal or cut the required length from a strip of the desired width and bent, as above mentioned, to the form representing substantially a semi-circle. The free ends of arms 16y—11y and 12y—13y of spacer member S1y, the free ends of arm 14y—15y and that of arm 16y of spacer member S2y and the free ends of arms 17y—18y of rectilinear spacer member S3y serving, as above mentioned, as bearing edges on which these spacer members are adapted to rest onto the adhesive covered supporting surface for the tiles.

In an actual aligning and spacing operation of tiles on an adhesive covered supporting surface, as the sub-floor shown in FIGS. 4 and 5, the tiles as T1, T2, T4, T5 and T6 for example, and one of the sets of spacer members as S1, S2 and S3, or S1y, S2y and S3y, are placed at random or approximate relation to each other and relative to the straight edges ST1 and ST2, and this followed by a side way movement of each of these straight edges 7

disposed at right angles to each other for moving the tiles and the spacer members in abutment against each other, which abutment occurs when the tiles are in aligned relation and spaced according to the width of the arms of the spacer members in their respective position relative to the tile and to the baseboard of a wall when the spacer members may be removed from between the tiles in a convenient manner by gripping with the fingers that portion of the spacers which extends above the top surface of the tiles, while the small contact area of the bearing ends of the arms of the respective spacer member resting over the adhesive on the supporting surface permits the removal of the spacer members from such surface without disturbing the alignment of the tiles.

What I claim is:

1. A tile spacer member consisting of a number of integrally formed half-crescent shaped arms extending at right angles to each other from a common junction point, the remote ends of said crescent-shaped arms being free and forming bearing means adapted to rest over a supporting surface, the junction point of said arms being adapted to form means serving for placing on and removing said spacer member from the supporting surface.
  2. A combination of tile spacer members adapted for use for spacing tiles on a supporting surface at different locations relative to a wall, each of said members having a plurality of arms each forming one-half of a crescent-shaped figure extending radially at a distance substantially equal from a common junction point to form respectively a cross, a capital letter T and an oblong-shaped figure, the remote ends of said crescent-shaped arms being free and adapted to rest on the supporting surface for the tiles.
  3. A tile spacer member for use for aligning and spacing tiles on a supporting surface, said member comprising a plurality of integrally formed arms extending from a common junction point at different angles relative to each other, each of said arms being bowed to form semi-circles, the end portions of said bowed arms forming bearing edges for supporting said member on the supporting surface for the tiles, the junction point of said bowed arms forming means adapted to be gripped by the fingers for placing in or removing said spacer member from the supporting surface for the tiles.
  4. A combination of tile spacer members of the class described for use for aligning and spacing tiles on an adhesive covered supporting surface, a number of said spacer members being derivative of one of said spacer members which is basic, said members having different numbers of bowed integrally formed arms of variable thickness from their point of junction to the free ends thereof generated by a radius from different center points, said arms being disposed in angular relation to each other to form respectively a double crescent representing a cross, a crescent joined to a semicrescent representing a capital letter T and two arms representing a crescent-shaped figure, the free ends of said arms of each of said spacer members forming narrow edge bearing means adapted to rest on the adhesive covering the supporting surface for the tiles.
